DESIGN FOR A SPECTACLE CASE

Saul L. Lachter, Maplewood, N. J.

Application July 20, 1938, Serial No. 78,608

Term of patent 7 years

To all whom it may concern:

Be it known that I, Saul L. Lachter, a citizen of the United States, residing in the township of Maplewood, in the county of Essex and State of New Jersey, have invented a new, original, and ornamental Design for a Spectacle Case, of which the following is a specification, reference being had to the accompanying drawing, forming part thereof.

In the drawing,

Fig. 1 is a plan view of a spectacle case, showing my new design,

Fig. 2 is a side elevational view thereof, and

Fig. 3 is an enlarged fragmentary sectional view taken on line 3—3 of a top portion of Fig. 1.

I claim:

The ornamental design for a spectacle case, as shown.

SAUL L. LACHTER.
